UNITED STATES PATENT OFFICE.

PAUL RUSSELL CUMMING, OF KANSAS CITY, MISSOURI, ASSIGNOR OF ONE-HALF TO CHARLES I. PETTIBONE, OF SAME PLACE.

DESIGN FOR A WINDOW-CLEANER.

SPECIFICATION forming part of Design No. 28,990, dated July 5, 1898.

Application filed April 16, 1898. Serial No. 677,893. Term of patent 14 years.

To all whom it may concern:

Be it known that I, PAUL RUSSELL CUMMING, a citizen of the United States, residing at Kansas City, in the county of Jackson and State of Missouri, have invented and produced a new and original Design for a Window-Cleaner, of which the following is a specification, reference being had to the accompanying drawings, forming a part thereof, in which—

Figure 1 is a perspective view of a window-cleaner embodying the features of my design, and Fig. 2 is a transverse section through the cleaner.

The leading features of the design consist in a head delineated by two concentric segmental plates A and B, the plate A terminating at the sides in the oppositely-inclined

aprons *a a* and the plate B terminating in the oppositely-inclined aprons *b b*, the inclined 20 aprons at each side of the head being similar.

Other features of the design consist in a filling D between the segmental plates provided with diverging skirt-sections D', which pass between the aprons *a* and *b* of the segmental plates, extending beyond said aprons, the filling being provided with corrugations on its outer face and a claw-handle E, that grasps the head.

I claim—

The design for the window-cleaner, substantially as herein shown and described.

PAUL RUSSELL CUMMING.
